TRUCK SIDE FRAME

Application filed November 12, 1929. Serial No. 406,678.

This invention relates to improvements in side frames, more particularly to improvements in the strengthening means employed for the spring seat section to provide for uniform deflection of the tension and compression members.

It has been found in making side frames, especially of the wider types for high capacity cars, that it is necessary to make the frame very wide and some means must be employed in order to provide for uniform deflection of the tension and compression members of the spring seat section and therefore for uniform strength distribution. According to previous practice, additional ribs or webs have been employed within the box section of the spring seat member, but certain objections have been raised to such a construction, since it is not good foundry practice to have intersecting walls.

It is an object of the present improvements to provide tubular strengthening means for the spring seat section, whereby there can be a uniform flow of metal at the intersecting points of the tubular strengthening means and the webs of the spring seat section.

A further object of the present invention consists in providing a pair of tubular strengthening portions disposed on opposite sides of the center line of the side frame between the walls of the spring seat section.

Additional objects and advantages of the present improvements will be more readily apparent from the following description, taken in connection with the attached drawings, in which:

Figure 1 is an elevation of the portion of a side frame illustrating a single tubular strengthening member extending between the webs of the spring seat section;

Figure 2 is a partial bottom plan view of the side frame illustrated in Figure 1;

Figure 3 is a transverse section taken along the center line of the side frame illustrated in Figure 1;

Figure 4 is a partial elevation of a portion of a spring seat section of a side frame illustrating a pair of tubular strengthening members disposed between the upper and lower webs of the spring seat section;

Figure 5 is a partial bottom plan view of the spring seat section illustrated in Figure 4;

Figure 6 is a transverse section taken along the center line of Figure 4;

Figure 7 is a partial side elevation of a further modification of a side frame embodying the improvements of the present invention in which the diameter of the tubular strengthening members increases towards the upper web of the spring seat section;

Figure 8 is a partial bottom plan view of the side frame illustrated in Figure 7;

Figure 9 is a broken transverse section taken in part on the center line of the side frame illustrated in Figure 7; and in part through the center of the tubular connecting member;

Figure 10 is a partial detail section taken on the plane indicated by line 10—10 in Figure 8;

Figure 11 is a partial illustration of a spring seat section illustrating a further modification;

Figure 12 is a bottom plan view of the spring seat section illustrated in Figure 11; and

Figure 13 is a transverse section taken along the section line 13—13 of the spring seat section as indicated in Figure 11.

In accordance with the usual practice, the side frame illustrated in Figure 1 includes an upper compression member 10 and a lower tension member 11 integrally connected at their converging ends to journal boxes 13.

The tension and compression members are spaced at their center portions in parallel disposition and braced by columns or struts 14 to define a window 15 adapted to receive a customary bolster. The tension and compression members as shown are of channel section.

Thus the compression member has an upper web 16, depending flanges 17 and a beaded edge 18, while the tension member has a lower web 19 and upwardly extending flanges 20 terminating in a beaded edge 21. The columns 14 also are of channel section and include an inner web 22 and flanges 23 terminating in a beaded edge 24. The tension and compression members and the columns

are so joined together that their flanges merge with each other and the beaded edges form a continuous strengthening rib around openings 25.

- 5 The portion of the tension member at the bottom of the window 15 forms a spring seat section 26 and this section is of box shaped formation comprising a lower tension web 27 and an upper compression web or shelf 10 28. Suitable openings 29 are provided in the lower web 27 at the ends of the box section to permit drainage of accumulated moisture. The upper web 28 of the spring seat section is widened as shown by the lateral flanges 15 30 and side walls 32 of the spring seat section.

If a side frame of the type so far described is made sufficiently wide, it becomes necessary to provide additional strengthening means between the upper and lower webs 27 and 28 20 of the spring seat section. Straight ribs or webs have been utilized, but have proved unsatisfactory. According to our improvements, we employ a tubular member 33, which in the present instance is disposed at the 25 center line of the side frame and extends vertically between the lower and upper webs 27 and 28 of the spring seat section. The tube 33 serves to tie together the webs of the spring seat section and provide for uniform deflection. It is apparent that this construction avoids intersecting walls and the metal is free to flow at the intersections of the tube with the webs.

According to the modification disclosed in 35 Figures 4, 5, and 6 in which similar reference numbers have been employed as far as possible, we have shown a pair of tubular strengthening members, 34 and 35. The tubes in this modification are each of elongated shape in the direction of the plane of 40 the side frame. In Figures 4 and 5 the bosses 36 for the spring seat section are also illustrated.

As a further modification there is illustrated in Figures 7 to 10 a modified form of 45 side frame in which the tubular strengthening portions widen towards their upper ends. Thus the tubes 37 and 38 disposed on opposite sides of the center line and between the upper and lower webs of the spring seat section 50 are substantially conical in form. Thus the openings 39 and 40 through the lower web 27 are smaller than the openings 47 through the upper web 28. This construction 55 is possible because additional metal can be removed from the upper web without sacrificing strength. To compensate for the openings through the webs we may make the lower web 27 somewhat wider than customary and 60 portions of the walls as illustrated at 41 incline outwardly toward the upper web 28.

A further modified manner of utilizing 65 tubular strengthening for the spring seat portion of a side frame is illustrated in Figures 11 to 13 in which similar reference char-

acters are employed as far as possible as in the previous figures. According to this embodiment the drain openings 29 in the web 19 of the tension member are extended into the web 27 of the spring seat portion between 70 the walls 42 and 43. The walls 42 and 43 extend between the upper and lower webs as shown by the dotted line 44 in Figure 11 and finally merge into the top web 28. The walls 42 and 43 further merge into each other 75 at the curved and inclined portion 45. Finally to provide strengthening means between the walls 42 and 43, a strengthening tube 46 is provided as shown in section in Figure 13, extending between the walls 42 80 and 43. This construction also does away with intersecting walls and tends to hold the lower web 27 in proper relation to the load conditions.

It will be obvious that many other modified 85 constructions may be employed for substantially the same purposes as the present invention, and it will be understood that we intend to cover all such modifications as come within the spirit of the appended claims. 90

We claim:

1. In a side frame, a box-shaped spring seat section and tubular strengthening means between the webs of the spring seat section. 95
2. In a side frame, a spring seat section box-shaped in formation and tubular strengthening means tying together the upper and lower webs of the spring seat section. 100
3. In a side frame, a box-shaped spring seat section and a pair of tubular strengthening portions disposed on opposite sides of the center line of the side frame between the upper and lower webs of the spring seat section. 105
4. In a side frame construction, a spring seat section box-shaped in formation and tubular means tying together the upper and lower webs of the spring seat section without the provision of intersecting walls. 110
5. In a side frame construction, a spring seat portion, box-shaped in formation, including a pair of walls forming continuations of the upper and lower webs and a tubular portion between said walls. 115
6. In a side frame, a box-shaped spring seat section and an integral substantially tubular reinforcement between the upper and lower webs of the spring seat section. 120
7. In a side frame, a box-shaped spring seat section, the upper and lower webs of said spring seat section having openings therein, re-entrant portions extending inward and defining the edges of the openings, said re-entrant portions merging together within the box-shaped section. 125
8. In a side frame including a portion substantially box-shaped in section adapted to receive a transverse load, an integral tubular reinforcement extending between opposed walls of said box-shaped portion and parallel 130

to the direction of said load, said walls having openings at the ends of said reinforcement each having an area at least equal to the minimum cross-sectional area of the 5 opening in said reinforcement.

9. In a side frame including a portion substantially box-shaped in section, arranged horizontally and adapted to receive a vertical load, an integral tubular reinforcement ex- 10 tending between the upper and lower walls of said box-shaped portion, said walls having openings at the ends of said reinforcement each having an area at least equal to the minimum cross-sectional area of the opening in 15 said reinforcement.

Signed at St. Louis, Missouri this 8th day of November, 1929.

HARRY C. DREIBUSS.
GEORGE S. CHILES.
